UNITED STATES PATENT OFFICE.

RAY C. NEWHOUSE, OF WAUWATOSA, WISCONSIN, ASSIGNOR TO ALLIS-CHALMERS
MANUFACTURING COMPANY, OF MILWAUKEE, WISCONSIN, A CORPORATION OF
DELAWARE.

PROCESS OF TREATING COMBUSTIBLE MATERIAL.

Application filed April 17, 1922. Serial No. 554,285.

This invention relates in general to improvements in the art of handling and of conditioning materials, and relates more specifically to an improved process of comminuting, transporting, drying and otherwise treating combustible substances such as pulverized coal.

An object of the invention is to provide a simple and efficient process of conditioning combustible substances. Another object of the invention is to provide a process of drying combustible materials without danger of explosion. Another object of the invention is to provide a process of safely comminuting combustible material. A further object of the invention is to provide a process of removing combustible material from a comminuting device and for safely transporting such material. Still another object of the invention is to provide a process of automatically conditioning and delivering pulverulent fuel such as coal to a combustion chamber. These and other objects and advantages of the present invention will be apparent from the accompanying specification.

A clear conception of the several steps of the novel process and of one embodiment of apparatus for commercially exploiting the same, may be had by referring to the drawing accompanying and forming part of this specification, in which like reference characters designate the same or similar parts in the several views.

Fig. 1 is a somewhat diagrammatic part sectional side view of a fuel conditioning and utilizing installation.

Fig. 2 is a transverse vertical section through a material reducing or comminuting mill adapted for exploitation of the improved process.

The fuel conditioning and utilizing installation shown in the drawing, comprises generally comminuting means for reducing the fuel to pulverulent condition, means for treating the pulverized fuel to condition the fuel for utilization in a combustion chamber, fuel transporting means, and a combined combustion chamber and heat absorbing device.

The specific reducing means herein illustrated, comprises a rotary comminuting mill 2 forming a confined chamber or space within which a plurality of freely tumbling com-

minuting bodies 14 such as rods, or balls, 55 are located. The interior of the mill 2 may be provided with liners 15 formed to automatically elevate and precipitate the fine material 16 through the free space within the mill during rotation thereof. The mill 2 is provided with inlet and discharge passages located within end supports formed as hollow trunnions 12, 13, the feed or inlet trunnion 12 communicating with the gas supply conduit 8 and with a coarse material 65 supply bin 10, and the discharge trunnion 13 communicating with a comminuted material and gas mixture conducting pipe 11. The delivery end of the pipe 11 communicates with a tangential pulverized material 70 and gas mixture inlet 17 leading into a centrifugal or cyclone separator 3 which is adapted to preliminarily separate the relatively coarser particles of reduced material from the dust and gas. The gas and dust 75 mixture discharge pipe 18 connects the upper central portion of the separator 3 with the dust laden gas inlet of a fabric bag type of dust collector 4, of the type illustrated in U. S. Patent 1,168,543, granted 80

January 18, 1916, having a purified gas discharge which communicates with the suction fan 22. The solids delivery pipe 19 of the separator 3 and the dust discharge

hopper 21 of the dust collector 4, communicate with a conveyor trough having therein a continuously operable helical or screw conveyor 20. The delivery end of the screw conveyor 20 communicates with a fuel

hopper or bin 23 the lower extremity of 90 which communicates with a conveyor conduit having therein a continuously operable helical or screw conveyor 24. The discharge of the screw conveyor 24 is directed toward the fuel injection pipe 27 in front of

the air injection nozzle 26. A pressure blower 25 communicates with the injection nozzle 26 and is adapted to force air and pulverized material through the injection pipe 27 into the combustion chamber 5. 100

The combustion chamber 5 may be provided with additional air inlet openings 28, and communicates with a steam boiler heating chamber 6 or other heat absorbing device. The boiler heating chamber 6 has com- 105

munication with a stack 7 through which the waste gases of combustion may be discharged. A gas return pipe 8 connects the

stack 7 with the inlet trunnion 12 of the comminuting mill 2, this pipe 8 preferably being provided with a flow control valve and with a fresh air inlet valve 9.

- 3 During normal operation of the installation and commercial exploitation of the novel process, the raw material ordinarily relatively coarse coal, is being delivered from the supply bin 10 to the comminuting mill 2 through the inlet trunnion 12, and pulverized fuel is being burned in the presence of air, in the combustion chamber 5. The freely tumbling comminuting bodies 14 in the mill 2 reduce the coarse fuel and the liners 15 shower the fine material 16 through the free space within the mill 2 as indicated in Fig. 2. Due to operation of the suction fan 22, gaseous products of combustion and possibly a small amount of air are drawn through the interior of the mill 2. The heated gases flowing through the comminuting chamber at relatively high velocity, cause the pulverulent material 16 to intermingling therewith and the mixture of gas and suspended solids passes through the pipe 11 and into the cyclone separator 3 through the tangential inlet 17. In the separator 3 the coarser particles are removed from the mixture and are delivered directly into the path of the screw conveyor 20, while the remaining dust and gas mixture is delivered to the dust remover or collector 4. In the dust collector 4 the dust is removed and delivered directly to the screw conveyor 20 while the gases are discharged through the suction fan 22. The screw conveyor 20 delivers all of the pulverulent fuel removed by the separator 3 and collector 4 to the fuel bin 23, which in turn delivers a continuous stream of the powdered coal into the path of the air jet delivered from the injection nozzle 26, through the screw conveyor 24. The mixture of fuel and air produced in the injection pipe 27 is delivered as a continuous stream into the combustion chamber 5, wherein it is automatically ignited and burned. The hot products of combustion generated in the combustion chamber 5 pass through the steam boiler heating chamber 6, wherein considerable of the heat is absorbed. The spent gases of combustion are discharged through the stack 7 in relatively hot condition, a portion of these spent gases being withdrawn through the pipe 8 and delivered to the mill 2.

It will be obvious that the process is both automatic and continuous. The hot gases of combustion delivered to the comminuting mill 2 through the pipe 8, serve to simultaneously transport and dry the fine material 16. By employing gases of combustion or other gas containing relatively small quantities of uncombined oxygen, danger of explosions in the system, is entirely eliminated. The temperature of the gas admitted to the

mill 2 may be regulated by controlling the admission of air through the valve 9. The cyclone separator 3 and dust collector 4 serve to effectively remove the fine fuel from the transporting and drying gas, and the screw conveyors 20, 24 effectively control the delivery of fuel to the combustion chamber 5. It will also be obvious that by employing only a gas current to deliver comminuted material from the mill 2, undesirably coarse particles of material cannot be discharged. While the process has been specifically described as applied to the treatment of coal, it will be obvious that the steps of the process are generally applicable to the treatment of many other substances.

It should be understood that it is not desired to limit the invention to the exact details of construction and operation of the apparatus shown, nor to the exact steps of the process, for obvious modifications within the scope of the claims, may occur to persons skilled in the art.

It is claimed and desired to secure by Letters Patent:

1. The process of treating and utilizing combustible material, which comprises, comminuting the material within a confined zone, passing a blast of non-combustible gas through said zone to remove fine material therefrom, separating the removed material from the gas, delivering the removed material to a heated zone, burning the material in said heated zone, and returning non-combustible gas to said comminuting zone to remove subsequent material therefrom. 100

2. The process of treating and utilizing combustible material, which comprises, comminuting the material within a confined zone, passing a blast of gaseous products of combustion through said zone to remove fine material therefrom, separating the removed material from said products of combustion, delivering the removed material to a heated zone, burning the material in said heated zone, and returning products of combustion from said heated zone to said comminuting zone to remove subsequent material therefrom. 110

3. The process of treating and of utilizing combustible material, which comprises, comminuting and showering the material within a confined zone, removing floating material only from said zone by passing there-through a blast of non-combustible gas containing insufficient quantities of uncombined oxygen to support combustion, separating the removed material from the gas, delivering the removed material to a heated zone, burning the material in said zone, and returning non-combustible gas to said comminuting zone to remove subsequent material therefrom. 115

4. The process of treating and utilizing combustible material, which comprises, com- 120

minuting and showering the material within a confined zone, removing floating material only from said zone by passing therethrough a blast of gaseous products of combustion containing insufficient quantities of uncombined oxygen to support further combustion, separating the removed material from said products of combustion, deliver-

ing the removed material to a heated zone, burning the material in said heated zone, ¹⁰ and returning products of combustion from said heated zone to said comminuting zone to remove subsequent material therefrom.

In testimony whereof, the signature of the inventor is affixed hereto.

RAY C. NEWHOUSE.
